(57) **CLAIM**

The ornamental design for an infrared radiation dryer, as shown and described.

DESCRIPTION

FIG. 1 is a right side view of an infrared radiation dryer, according to a first embodiment;

FIG. 2 is a left side view thereof, according to the first embodiment;

FIG. 3 is a top view thereof, according to the first embodiment;

FIG. 4 is a bottom view thereof, according to the first embodiment;

FIG. 5 is a front thereof, according to the first embodiment; FIG. 6 is a back view thereof, according to the first embodiment; and,

FIG. 7 is a perspective view thereof, according to the first embodiment.

Note that any broken line illustration of environmental structure in the drawing is not part of the design sought to be patented.

1 Claim, 4 Drawing Sheets
